UNITED STATES PATENT OFFICE.

GEORGE HATCH FLINT, OF BELLFLOWER, ILLINOIS

SHIELD-HOLDER FOR CULTIVATORS.

1,110,048.

Specification of Letters Patent. Patented Sept. 8, 1914.

Application filed April 29, 1914. Serial No. 835,195.

To all whom it may concern:

Be it known that I, GEORGE HATCH FLINT, a citizen of the United States, residing at Bellflower, in the county of McLean and

5 State of Illinois, have invented certain new and useful Improvements in Shield-Holders for Cultivators, of which the following is a specification, reference being had to the accompanying drawings.

10 This invention relates to cultivators, and more particularly to a novel form of fender or shield holder therefor, the invention being more particularly adaptable for use in connection with cultivators having an arch 15 for holding the points, knives, or disks together.

As is well known, when the disks of a cultivator are set close together for plowing small corn, the rolling of the disks presses 20 the dirt against the shields and lifts them above the corn unless the shields are rigidly held down, and when held down at the right height, then the disks push the dirt up under the shields around the corn.

25 The object of the present invention is in a ready and practical manner so to combine the shields with the arch as to permit of their being readily adjusted to any degree to insure the protection of the young 30 plants, and to accomplish this result without necessitating any extended change in the structural arrangement of an ordinary cultivator employing an arch and shields of the character described.

35 With the above and other objects in view, as will appear as the nature of the invention is better understood, the same consists in the novel construction and combination of parts of a shield holder for cultivators, as will be hereinafter fully described and claimed.

40 In the accompanying drawing, forming a part of this specification, and in which like characters of reference designate corresponding parts: Figure 1 is a view in rear elevation of a cultivator, showing the improvements of the present invention applied thereto, the cultivator being indicated by dotted lines; Fig. 2 is a side elevation 45 of the shield attachment. Fig. 3 is a detailed sectional view taken on the line 3—3 of Fig. 1.

50 Referring to the drawing, 1 designates the arch of the cultivator, 2 the frame for the wheel axles, 3 the ordinary draw bars that connect the disk carrying frames with

the frame of the machine, and 4 the disks, and as these parts may be of the usual or any preferred construction, further description thereof is deemed unnecessary.

50

The present invention resides in a novel manner of supporting the fenders or shields 5 from the arch in such a manner as positively to prevent their being lifted from the action of the disks, whereby the young 65 plants may be protected, and further in the novel means for adjusting and maintaining the shields in adjusted position.

60 The shields may be of the usual or any preferred construction, and are carried by 70 angle irons 6 which are firmly bolted or riveted to the shields and hold the latter in parallelism at their front portions. The upper ends of these angle irons overlap and are orificed to receive an eye bolt 7 which 75 is held assembled with the angle irons by a nut 8. The shields have connected with them, at their sides, the lower ends of a pair of draw rods 9 the upper ends of which 80 are pivoted to the frame in the usual manner. Connecting with the eye 10 of the bolt 7 is an eye 11 carried by the lower end of a rod 12 the upper end of which is threaded throughout a considerable portion 85 of its length and passes through an eye bolt 13 that is carried by the crest of the arch and held assembled therewith by a nut 14. On each side of the eye 13 and threaded on the rod is a nut 15, and these 90 two nuts may be manipulated to raise or lower the rod 12, and also to lock it in its adjusted position. In order to brace the rear portions of the shields against spreading and also hold them in parallelism there is connected to each shield, adjacent its rear end, angle bars 16, similar to the bars 6, the upper ends of which overlap as indicated at 17 and are held assembled by a bolt passing through the overlapped parts.

95 From the foregoing description it will be seen that in order to apply the invention to an ordinary cultivator provided with an arch, it will only be necessary to provide the latter with an orifice to receive the eye bolt 13 and then position the rod 12, nuts 15 and shields.

The improvements are simple in character and will be found thoroughly effective for the purposes designed, and in operation positively shield young plants from injury.

Having thus described my invention, what I claim is:

The combination with the arch of a cultivator, an eye bolt removably arranged in the crest of the arch, a threaded rod extending through the eye bolt having an eye formed upon its lower end, jam nuts arranged upon the threaded rod and upon opposite sides of the bolt, a pair of shields arranged in spaced parallel relation and braced at their rear ends, angle irons secured to the sides of the shields and extending over the top thereof, an eye bolt

extending through the angle irons, jam nuts arranged upon the eye bolt and arranged upon opposite sides of the angle irons, and the eye of the threaded rod being connected in the eye bolt whereby the shields are held against lifting.

In testimony whereof I hereunto affix my signature in the presence of two witnesses.

GEORGE HATCH FLINT.
